SELF-SUSTAINING GAS TUBE CIRCUIT

William Merle Webster, Jr., Princeton, N. J., assignor to Radio Corporation of America, a corporation of Delaware

Application January 2, 1951, Serial No. 203,950

9 Claims. (Cl. 315—349)

1

This invention relates to improvements in systems for operating gas filled electron tube circuits, and particularly to an improved system for operating a gas filled electron tube of the type wherein the functions of ionizing the tube gas and of passing current through the ionized gas are separated.

In a copending application of E. O. Johnson, Serial No. 185,745, filed September 20, 1950, and assigned to the assignee of the present invention, there is described a gas filled electron tube in which space charge neutralizing ions are generated by an auxiliary ionizing discharge of electrons between an auxiliary emitter and one or more of the main tube electrodes. With this arrangement, two very important advantages are attained.

First, it is found that very high current can be passed between the main emitter and collector electrodes at potentials far below those required to ionize the gas. Second, it is found that the current flow between main emitter and collector can be controlled in various ways, one of which is by means of a control electrode similar to that used in the conventional vacuum tube.

For simplicity, gas tubes of the type just described are referred to herein as "separated function" gas tubes.

While the principal current through a separated function gas tube can be sustained with a voltage considerably less than that required to ionize the tube gas, it is still necessary to have a voltage of sufficient amplitude to sustain the auxiliary ionizing discharge.

In a copending application of H. N. Crooks, Serial No. 248,771, filed September 28, 1951 and assigned to the assignee of the present invention, there is disclosed what may be termed a self-sustaining oscillatory gas tube circuit. In the system disclosed in said Crooks application, a separated function gas tube is connected in an oscillatory circuit from which stepped-up alternating voltage is derived and rectified to provide a voltage which will sustain an ionizing discharge, so that the primary source of operating voltage can be less than that required to ionize the tube gas.

It is a principal object of the present invention, to provide an improved self-sustaining circuit for operating a separated function gas tube with a source of voltage less than that required to ionize the tube gas.

A more specific object of the invention is the provision of an improved and simplified arrangement for initiating the operation of a self-sustaining gas tube circuit.

2

Another object of the invention is to provide an improved direct current inverter network comprising a self-sustaining gas tube circuit.

An ancillary object of the invention is to provide an improved separated function gas tube.

In accordance with the invention, certain of the foregoing objects and advantages are attained by utilizing oscillatory voltage developed by a separated function gas tube circuit prior to ionization of the tube gas. This oscillatory voltage is stepped-up by a transformer sufficiently to provide an ionizing voltage for the tube gas. In accordance with a further feature of the invention, this stepped-up alternating voltage may be converted to unidirectional voltage by rectification in the ionization section of the gas tube. A further feature of the invention provides a gas tube structure especially adapted to prevent "backfiring" or inverse current flow in a gas tube energized in accordance with the invention.

A more complete understanding of the invention may be had by reference to the following description of illustrative embodiments thereof, when considered in connection with the accompanying drawing, wherein:

Fig. 1 is a schematic diagram of a self-sustaining gas tube oscillator system arranged in accordance with the invention.

Fig. 1a shows the structure of a gas tube such as may be used in the circuit of Fig. 1.

Fig. 2 is a schematic diagram of a direct current inverter network embodying the principles of the invention.

Fig. 2a illustrates the structure of a gas tube especially adapted for use in the circuit of Fig. 2 and embodying certain principles of the invention.

Fig. 3 is a graph illustrating the operation of the network of Fig. 2, and

Fig. 4 is a circuit diagram of a modification of the network of Fig. 2 embodying the principles of the invention.

Referring to Fig. 1 of the drawing, a circuit embodying the invention includes a gas filled electron tube 10, structural details of which are given hereinafter. The tube 10 is provided with an anode 12 and a main cathode 14, with a control electrode 16 therebetween. The anode 12 and control electrode 16 are connected to opposite ends of a tank circuit 18 through capacitors, 20 and 22, respectively. The cathode 14 is connected to an intermediate point on the coil 24 of the tank circuit 18 to complete a so-called Hartley oscillator network. The coil 24 also serves as the primary winding of a transformer

25, for a purpose explained hereinafter. A variable capacitor 39 is provided for tuning the tank circuit 18.

A battery 26 is shown to represent a source of voltage less than that required to ionize the tube gas. The battery 26 is connected to the anode 12 and to the cathode 14 (through the coil 24) to energize the oscillator circuit.

The tube 10 also is provided with an auxiliary cathode 28, cooperable with the anode 12 or the cathode 14, or both, to ionize the gas in the tube 10. In order to provide a voltage of sufficient amplitude to ionize the tube gas, the auxiliary cathode 28 is connected through a rectifier 30 to the secondary winding 32 of the transformer 25.

In a somewhat similar system described in the above-mentioned Crooks application, circuit operation is initiated by temporarily connecting the voltage source to the tank coil to obtain in the ionizing circuit an induced voltage of sufficient amplitude to ionize the tube gas. In accordance with the present invention, this switch is eliminated.

Prior to ionization of the tube gas, the main tube electrodes 12, 14 and 16 will cooperate with the tank circuit 18 to develop a small oscillatory voltage across the tank circuit 18. By providing very close coupling between the transformer windings 24, 32, and making the ratio of secondary to primary turns relatively high, this small tank circuit voltage can be stepped-up sufficiently to cause the rectifier 30 to conduct and charge a capacitor 34 connected in series therewith. The capacitor 34 also is connected between the auxiliary cathode 28 and the voltage source 26. As soon as the sum of the capacitor voltage and the source voltage is large enough to ionize the tube gas, ionizing current will flow from the auxiliary cathode 28 to the main anode 12. Upon ionization of the tube gas, the main cathode-anode current of the tube 10 will increase substantially, causing a corresponding increase in the oscillatory voltage developed across the tank circuit 18. In turn, this oscillatory voltage will be coupled into the ionizing circuit through the transformer 25 to maintain ionization of the tube gas. If desired, the stepped-up voltage developed across the capacitor 34 also can be made available for energizing other circuits which may be connected to a pair of output terminals 36.

Thus, prior to ionization of the tube gas, the tube 10 can be said to operate as a vacuum tube, generating a small oscillatory voltage in the tank circuit 18. As soon as the tube gas becomes ionized, the tube 10 will operate as a separated function gas tube, with the advantages of low voltage grid controlled current flow characteristic of such tubes.

Consider, for example, the tube shown in cross section in Fig. 1a. In Fig. 1a, a gas tight envelope 10 is provided with a cathode 14. A U-shaped control electrode or grid 16 and a U-shaped anode 12 partially surround the cathode 14. The grid 16 comprises a plurality of parallel wires 17 which are supported in spaced relation. The anode 12 may be a sheet metal element.

In order for the tube 10 to have sufficient amplification to start oscillation before ionization of the tube gas, it is deemed preferable to modify the grid and anode structures slightly. A mesh-type grid section 16a may be provided at a point relatively close to the cathode 14, while an anode extension 12a may be brought close to the grid

section 16a. These closely spaced elements 16a, 12a will assist in setting up "pre-ionization" oscillations.

Opposite the open ends of the grid 16 and the anode 12 there is mounted a cylindrical focusing electrode 23 provided with an elongated slot 27 facing the open ends of the grid and anode structures. An auxiliary cathode 28 is mounted coaxially within the focusing electrode 23.

10 A tube having a structure such as that shown in Fig. 2 can be operated as follows:

If a voltage greater than that required to ionize the gas in the tube is applied between the auxiliary cathode 28 and the anode 12, a current 15 will flow which will ionize the gas in the tube. As a result, a highly conductive mixture or "plasma" of ions and electrons will be created within the tube envelope. The focusing electrode 23 is effective to concentrate the ionizing current, making it possible to obtain high plasma densities with very small amounts of current or power. With the tube gas ionized to create plasma in the manner just described, it becomes possible to pass a relatively high current between 20 the main cathode and the main anode with a voltage drop which may be of the order of 0.1 volt or less. Furthermore, it becomes possible to control this main cathode-anode current by 25 means of a control electrode disposed in the space path as shown. In some instances, the focusing electrode is utilized to control the ionizing current in order to control the main tube current. Otherwise, the focusing electrode may 30 be connected directly to the auxiliary cathode 28, as in Fig. 1.

In accordance with a further feature of the present invention, the rectifier 30 of Fig. 1 can be eliminated without adversely affecting system operation, and in such manner that the system 35 still will function as a direct current inverter, furnishing stepped-up unidirectional output voltage from a low voltage source. A system illustrating this feature of the invention is shown in Fig. 2.

40 In the system shown in Fig. 2, a gas tube 10a is provided which is substantially the same as the tube 10 of Fig. 1. The tube 10a, however, preferably has one additional electrode; namely, an auxiliary control electrode 29 in the space 45 between the auxiliary cathode 28 and the main electrodes 12, 14, 16. The purpose of the auxiliary control electrode 29 will be explained hereinafter. The structure thereof may be as shown in Fig. 2a, comprising a plurality of parallel wires 50 31 supported in spaced relation adjacent the slot 27 in the focusing electrode 23.

The remainder of the circuit of Fig. 2 also corresponds substantially with the circuit of Fig. 1, with the exception that the rectifier 30 of Fig. 1 is eliminated in the circuit of Fig. 2.

In a copending application of I. Wolff, Serial No. 212,632, filed February 24, 1951, and assigned to the assignee of the present invention, there is described a self-sustaining oscillator system embodying a separated function gas tube, in which a pulse voltage is utilized to support the auxiliary ionizing discharge. This principle is, in part, utilized in the embodiment of the present invention shown in Fig. 2.

The operation of the circuit of Fig. 2 can best be explained in connection with the chart of Fig. 3.

In Fig. 3, the broken line A is taken as the principal reference, and represents the D. C. voltage at the lower output terminal 36b of

Fig. 2. The dot-dash line B represents the voltage at the anode 12, being separated from the reference line A by a distance E_b which represents the voltage of the battery 26. The broken line C represents the voltage level to which the auxiliary cathode 28 must be driven to ionize the tube gas. Thus, the line C is separated from the line B by a distance E_i , representing the ionization potential of the tube gas. A line D represents the D. C. voltage at the upper output terminal 36a, and is separated from the reference line A by an increasing distance E_o , representing the output voltage available between the terminals 36a, 36b. An undulating line F represents the alternating voltage at the auxiliary cathode 28, as induced in the secondary winding 32.

Prior to ionization of the gas in the tube 10a, a relatively small oscillatory voltage will be developed in the tank circuit 18, as in the circuit of Fig. 1. This voltage will be coupled into the secondary winding in amplified form. Eventually, as at point F₁ in the chart of Fig. 3, the sum of induced voltage and the battery voltage will be sufficient to cause an ionizing current pulse to flow from the auxiliary cathode 28 to the anode 12. This current pulse will charge the capacitor 34 by a small amount, raising the level of the line D about which the auxiliary cathode voltage is fluctuating. Ionization of the tube gas will permit an increase in the main tube current, as previously described.

As is explained in the above-mentioned Wolff application, if voltage pulses of relatively high amplitude and repetition rate are applied to the ionizing electrodes of a separated function gas tube, the main tube current will be substantially independent of the ionizing current. Thus, the oscillations in the tank circuit 18 in Fig. 2 gradually will build up, providing increasing amplitude pulses of ionizing voltage until the circuit becomes stabilized in full oscillation. It will, of course, be understood that the chart of Fig. 3 gives a simplified picture of the circuit operation, and is given solely as an aid in explaining circuit operation.

Since the line A in Fig. 3 represents the D. C. voltage at the output terminal 36b, the same line also substantially represents the D. C. voltage at the main cathode 14. It can be seen from Fig. 3 that the auxiliary cathode voltage will be rather highly positive with respect to the main cathode 14 during each positive half cycle of the auxiliary cathode voltage. Consequently, it is possible that inverse current might flow from the main cathode 14 to the auxiliary cathode 28 during these positive half cycles of auxiliary cathode voltage. Such inverse current flow would, of course, be in a direction such as to discharge the capacitor 34, thereby interfering with the desired circuit operation. To prevent this possible inverse current flow or "backfiring," the auxiliary control electrode 29 is connected to the tank circuit 18 in common with the main control electrode 16. With this arrangement, it is merely necessary to make sure that the transformer windings 24, 32 are so connected that voltages of opposite phase will be applied to the auxiliary cathode 28 and to grids 16, 29. This, of course, is simply a matter of selecting the proper end of the secondary winding 32 for connection to the auxiliary cathode 28.

With alternating voltages of opposite phase applied to the auxiliary cathode 28 and to the auxiliary control electrode 29, the control elec-

trode 29 will be at a negative potential relative to the main cathode 14 when the auxiliary cathode 28 is positive. This will prevent inverse current flow and insure proper circuit operation.

5 In accordance with a further embodiment of the invention, the possibility of inverse current flow can be avoided by making the auxiliary ionizing electrode an electron collector or anode rather than an electron emitter or cathode. 10 This arrangement is illustrated in the circuit of Fig. 4.

In Fig. 4, a separated function gas tube 10b has no auxiliary control electrode, but is provided with an auxiliary anode 28a rather than 15 with an auxiliary cathode as in the circuit of Fig. 2. Otherwise, the circuit of Fig. 4 is identical with that of Fig. 2.

In operation of the system of Fig. 4, ionizing current will flow from the main cathode 14 to 20 the auxiliary anode 28a during those intervals when the alternating voltage induced in the secondary winding makes the auxiliary anode 28a sufficiently positive with respect to the cathode 14. During the alternate half cycles 25 of voltage across the secondary winding 32, there will be little likelihood of drawing electrons from the auxiliary anode.

It can be seen that the present invention provides a simple and efficient system for operating 30 a separated function gas tube from a source of voltage less than that required to ionize the tube gas.

What is claimed is:

1. In a system for operating a gas filled electron tube of the type having electrodes including an anode, a cathode, a control electrode therebetween, and an auxiliary electrode cooperable with one of said electrodes for passing ionizing current through the tube gas, in combination, 35 an oscillatory circuit connecting said anode, said cathode and said control electrode and including a first coil, a source of voltage less than that required to ionize said tube gas, said voltage source being connected between said anode and said 40 cathode to sustain low amplitude oscillations in said oscillatory circuit prior to ionization of said tube gas, and means connecting said auxiliary electrode to said one electrode through said voltage source to derive from said low amplitude 45 oscillations a voltage of sufficient amplitude, 50 when added to said source voltage, to ionize said tube gas, said means comprising a second coil having a relatively large number of turns as compared to said first coil and closely inductively 55 coupled to said first coil.

2. A system as defined in claim 1 wherein said auxiliary electrode comprises an anode electrode.

3. A system as defined in claim 1 wherein said auxiliary electrode comprises a cathode electrode.

60 4. A system as defined in claim 1 wherein said gas tube further includes a control electrode between said auxiliary electrode and said another electrode, and connections from said coils to said auxiliary electrodes to supply out-of-phase 65 voltages to said auxiliary electrodes from said coils.

5. In a system for operating a gas filled electron tube of the type having electrodes including an anode, a cathode, a control electrode therebetween, and an auxiliary electrode cooperable with one of said electrodes for passing ionizing current through the tube gas, in combination, 70 an oscillatory circuit connecting said anode, said cathode and said control electrode and including a first coil, a source of voltage less than that re-

quired to ionize said tube gas, said voltage source being connected between said anode and said cathode to sustain oscillations in said oscillatory circuit, a second coil coupled inductively to said first coil and having a greater number of turns than said first coil to induce across said second coil an alternating voltage substantially greater than said oscillatory voltage, a capacitor, and a series circuit consisting of said voltage source, said capacitor and said second coil connected between said auxiliary electrode and said one electrode to provide between said last named two electrodes a pulsating voltage of amplitude sufficient to sustain ionization of said tube gas and to provide across said capacitor a unidirectional voltage of amplitude greater than said source voltage.

6. A system as defined in claim 5 wherein said auxiliary electrode comprises an anode electrode.

7. A system as defined in claim 5 wherein said auxiliary electrode comprises a cathode electrode.

8. A gas filled electron tube having electrodes including an anode, a cathode, a control electrode therebetween, an auxiliary cathode cooperable with one of said electrodes for passing ionizing current through the tube gas, and a control electrode between said auxiliary electrode and said one electrode.

9. In a system for operating a gas filled elec-

tron tube of the type having a plurality of electrodes including a first pair of electrodes cooperable to pass ionizing current through the gas in said tube, a control electrode between said pair of electrodes to control said ionizing current, a pair of electrodes cooperable to pass current through the ionized gas, and a second control electrode between said last named electrode pair for controlling said last named current, in combination, a source of voltage less than that required to ionize said tube gas, an oscillatory circuit, connections between said oscillatory circuit, said last named electrode pair, said control electrode, and said voltage source for sustaining oscillations in said circuit upon ionization of said tube gas, means coupling said oscillatory circuit to said first named electrode pair to provide a voltage between said first named electrode pair sufficient to ionize said tube gas, and a capacitor connected between said first named electrode pair to be charged by said ionizing current flow.
